Frank DeVoe
BY

Augustus Detenich
his ATTORNEY.

UNITED STATES PATENT OFFICE.

FRANK DE VOE, OF LIMA, OHIO.

HYDROCARBON GENERATOR AND BURNER.

SPECIFICATION forming part of Letters Patent No. 631,779, dated August 29, 1899.

Application filed August 5, 1898. Serial No. 687,785. (No model.)

To all whom it may concern.

Be it known that I, FRANK DE VOE, a citizen of the United States, residing at Lima, Allen county, in the State of Ohio, have invented certain new and useful Improvements 5 in Hydrocarbon Generators and Burners, of which the following is a full, clear, and exact specification.

My invention relates to improvements in 10 apparatus for generating or producing gas from hydrocarbon compounds and utilizing the produced gas for heating and other purposes; and my invention has for its object more particularly to produce an efficient hydrocarbon generator and burner composed of 15 the smallest number of parts possible, which parts are so constructed and disposed in relation to each other and maintained in position to afford a free and unobstructed passage 20 for the flame without the use of bolts and nuts or analogous fastening devices. By means of my invention I am thus enabled to provide a generator and burner consuming a minimum amount of oil, yielding a more perfect and 25 economical vaporization and combustion, and producing a flame of intense heat substantially free from smoke, soot, odor, and noise.

A further feature of my invention is the separable character of the apparatus, which 30 enables the user to readily take the same apart for the purpose of cleaning or reversing the same when the apparatus is to be used as a "down" burner.

These objects above set forth I am enabled 35 to attain by means of my invention, which consists in the novel details of construction and in the combination, connection, and arrangement of parts, as hereinafter more fully set forth and then pointed out in the 40 claims.

In the accompanying drawings, forming part of this specification, wherein like letters of reference indicate like parts, Figure 1 is a top or plan view of a generator and burner constructed according to and embodying my 45 invention, one of the deflecting-plates being removed. Fig. 2 is a front view thereof, partly in section; and Fig. 3 is a section taken on the line 3 3 of Fig. 1.

50 In said drawings, A designates a base having an inclined face provided with support-

ing-lugs a a and an oil-pan B at its front and center, and C denotes a flange or rim extending around said base A.

Upon the base A, at its ends, are arranged 55 standards D D, and at the back of said base is arranged a standard E, and opposite thereto at the front of the base is a standard F, the standard E being made a trifle higher than the end standards D D and a trifle lower than 60 the standard F in order to properly support the front of the vaporizing-retort O and the flattened portion J of the frame P below the rear of said vaporizing-retort.

G denotes a frame comprising the hollow 65 cylindrical ends H H, united by a curved connecting-section I, provided midway of the distance between the cylindrical ends H H with a flattened portion J, having the apertures b b therein. K K denote supporting-brackets 70 which are formed integral with the ends H H and extend outward and upward therefrom, said frame G being cast integral with the base A and the standards D D and E, whereby to maintain said frame G permanently in position 75 above the base A.

L L denote mixers each composed of an annular section M, corresponding in diameter with and adapted to be supported upon the cylindrical ends H H and form a continuation 80 thereof. Within said cylindrical ends H H are supported, by means of radial arms d d, the central vapor-shells N N, having tapering openings N' N' therein, the radial arms d d being made integral with the annular sections M M and arranged adjacent to the lower edges thereof, but free of the inner surfaces of the cylindrical ends H H, and the vapor-shells N N being so disposed within said annular sections M M, and the cylindrical ends H 90 H that the tops of said vapor-shells shall be flush with the upper edges of the annular sections M M, and the lower ends of said vapor-shells project slightly beyond the lower edges of the cylindrical ends H H.

O denotes a vaporizing-retort supported at its back upon the connecting-section of the frame G and at its front upon the top of the standard F and maintained in position by means of the lugs e e, which depend from the 95 rear of the retort and extend into the apertures b b of the flattened portion J of the frame 100 P.

G. The said retort comprises an oil-receiving portion O', provided at its opposite ends with short pipe-sections P P', the section P' being provided with a cap P², while the section P is connected by a pipe Q with the source of oil-supply.

O² denotes the vaporizing portion of the retort, the base of which is provided with a raised central portion f, whereby to form annular pan portion g for the oil to be vaporized, and R denotes a vapor-delivery pipe which enters the retort from below and extends into said retort almost to the top thereof. From the lower end of said pipe R extend the branch pipe-sections R' R', the ends of which are adapted to rest upon the lugs a a of the base A, and provided in their upper portions, directly below the centers of the vapor-shells N N, with vapor-outlets h h, and in the top of the retort O², directly above the place where the delivery-pipe R enters the same, is provided an opening having a plug S, provided with recesses i i.

T denotes a U-shaped support provided upon the under side of its horizontal portion with studs j j, adapted to enter the recesses i i of the plug S, whereby to hold said support T in position upon the top of the retort O², and U U denote deflecting-plates pivotally supported upon the ends of the supporting-brackets K K and the support T, the deflecting-plates U U being provided upon their uppersurfaces with loop-sections k k, whereby the same may be removed.

35 The operation of the apparatus is as follows: After the initial firing a small quantity of oil is admitted by the pipe Q to the retort, which, having become intensely hot, at once vaporizes the oil and causes the same to collect in the dome-shaped top of the retort, whereby contact with the top of said retort the said vapor is converted into a fixed gas and thence conducted through the delivery-pipe R and branches R' R' and discharged from the outlets h, ignited and forced into the central vapor-shells N N of the mixers L L, where the vapor unites with a proper proportion of oxygen, and the mixture thence projected against the under sides of the deflecting-plates U U, when the combustion takes place.

Where it is desired to use the apparatus as a down burner, it simply becomes necessary to remove the deflecting-plates U U and the support T therefor, remove the plug S and the delivery-pipe R, and then secure the delivery-pipe R in an inverted position in the top of the retort and insert the plug S in the opening in the under side of the retort. The operation in this form will be substantially like that above described, except that the flame will be projected downward

against the base instead of upward against the deflecting-plates.

Without limiting myself to the details of construction, which may be varied within the scope of the invention, what I claim, and desire to secure by Letters Patent, is—

1. In a hydrocarbon generator and burner, a mixer comprising an outer shell consisting of two cylindrical sections, one of said sections resting upon the other, and a central removable shell having a tapering opening therein and provided with integral radial arms, said arms being arranged to contact with said outer shell, and a burner having a discharge-orifice in alinement with the opening through the central vapor-shell.

2. In a hydrocarbon generator and burner, a mixer comprising an outer drum composed of two cylinder-sections disposed one upon the other, a central vapor-shell having a tapering opening therein, and radial arms upon its outer surface adjacent to its top, said arms being integral with the vapor-shell and the upper cylinder-section, and extending downwardly beyond the lower edge of said upper cylinder-section and into the lower cylinder-section and adapted to contact with the inner surface thereof adjacent to its upper edge, a burner having a discharge-orifice in alinement with the opening through the central vapor-shell, and means for supporting said mixer and burner in operative relation, substantially as specified.

3. A hydrocarbon generator and burner, comprising a base, standards, and a curved frame portion, said frame having a flattened intermediate portion provided with apertures, a vaporizing-retort having depending lugs at its rear adapted to fit into said apertures and thus permit the rear portion of the retort to rest upon said flattened portion of the curved frame, the front portion of the retort being supported by one of the standards, an oil-supply and vapor-delivery pipe connected to and communicating with said retort, a mixer, and a burner, substantially as described.

4. A base or support for hydrocarbon generators and burners, comprising a base portion A, end standards D, front and rear standards E, F, a curved frame having an intermediate flattened portion provided with apertures, cylindrical portions H, H, and bracket portions K, K, all constructed in a single piece and for the purpose shown and described.

Signed at Lima, Allen county, in the State of Ohio, this 26th day of July, 1898.

FRANK DE VOE.
